UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 23,020, dated January 30, 1894.

Application filed October 18, 1893. Serial No. 488,546. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for the Handles of Spoons and other Similar Articles, of which the following is a specification, reference being had to the accompanying drawings, forming part of this specification, and in which—

Figure 1 is a face view of a spoon handle showing my design. Fig. 2 is a back view of same and Fig. 3 is a cross sectional view on line 3—3 Fig. 1.

The leading feature of my design consists in a panel produced upon the face of the handle and whose outlines will be more fully described hereinafter. This panel A widens out toward the upper end of the handle and has its upper end curved and extended laterally forming short wings a below which the edges of the panel curve inwardly at a' and below such curves a' the sides of the panel gradually converge nearly to the lower end of the handle, the straight lines of the edges of said panel being unbroken except by slight lateral extensions at a² a³. At its lower extremity the panel is divided at a⁴ and flared at a⁵ a⁶ as shown in Fig. 1.

The edge contour of the handle is waved or serpentine and upon the face outside the panel A is produced bead like representations which have scroll portions B extended within the curves a' and the bead like representa-

tions are extended within the space C between the head of the panel and the top of the handle producing the effect of passing below the wings a as shown. 35

A shield like representation D is produced upon the face of the handle between the top 40 of the panel A and the end of the handle and midway between the sides thereof as shown.

Upon the back of the handle bead like representations E are produced along the edge terminating at the upper end of the handle 45 in a spray like scroll.

In cross section the shape of the handle is curved producing a bulged effect upon the front and a dished or trough effect upon the back as most clearly shown in Fig. 3. 50

The coincident bead like representation upon the face and back of the handle produce a thickened effect at the edge of the said handle.

What I claim is—

1. In a design for a spoon handle or similar article, the obverse substantially as shown and described. 55
2. In a design for a spoon handle or similar article the reverse substantially as shown and described. 60
3. The design for a spoon handle or similar article herein shown and described.

AUSTIN F. JACKSON.
